United States Patent Office

Des. 234,237
Patented Feb. 4, 1975

234,237

CHAIR

Maxine Gibson, 750 Congo St., San Francisco,
Calif. 94131

Filed Mar. 8, 1973, Ser. No. 339,405

Term of patent 14 years

Int. Cl. D6—01

U.S. Cl. D6—26

FIG. 1.

FIG. 3.

FIG. 2.

FIG. 6.

FIG. 4.

FIG. 5.

FIG. 1 is a front view in perspective of a chair showing the features of my new design;

FIG. 2 is a reduced front view in perspective of the same but viewed from the side opposite from that of FIG. 1;

FIG. 3 is a reduced rear view in perspective of the same;

FIG. 4 is a view in front elevation of the same;

FIG. 5 is a view in side elevation of the same; and

FIG. 6 is a top view of the same.

I claim:

The ornamental design for a chair, substantially as shown and described.
